[57] CLAIM

The ornamental design for a combined lamp socket and track for low-voltage accent light, as shown and described.

DESCRIPTION

FIG. 1 is a front and upper left perspective view of a combined lamp socket and track for a low-voltage accent light showing my new design. The broken line showing of the bulb is included for the purpose of illustrating environmental elements only and forms no part of the claimed design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof; and,

FIG. 7 is a bottom plan view thereof.

FIG. 1**FIG. 2****FIG. 3****FIG. 4*****FIG. 5******FIG. 6******FIG. 7***
